UNITED STATES PATENT OFFICE.

LOUIS E. GOTTLÖB, OF ST. CLAIR, MISSOURI.

DESIGN FOR A CHAIR.

Application filed August 24, 1927. Serial No. 23,197. Term of patent 3½ years.

To all whom it may concern:

Be it known that I, LOUIS E. GOTTLÖB, a citizen of the United States, residing at St. Clair, county of Franklin, State of Missouri, have invented a new, original, and ornamental Design for a Chair, of which the following is a specification, reference being had to the accompanying drawing, which shows a perspective view of the chair.

I claim:

The ornamental design for a chair, as shown.

LOUIS E. GOTTLÖB.
